CLAIM

The ornamental design for a belt buckle or the like, as shown and described.

DESCRIPTION

FIG. 1 is a top perspective view of belt buckle or the like showing my new design;

FIG. 2 is a side perspective view;

FIG. 3 is a bottom isometric view;

FIG. 4 is a perspective view of a belt buckle or the like showing a second embodiment of my new design.

The bottom of the second embodiment is substantially the same as the bottom of the first embodiment save for the round periphery.
